UNITED STATES PATENT OFFICE.

HALBERT K. HITCHCOCK, OF PITTSBURGH, PENNSYLVANIA, ASSIGNOR TO PITTSBURGH PLATE GLASS COMPANY, A CORPORATION OF PENNSYLVANIA.

CAR-COUPING APPARATUS.

Application filed June 9, 1926. Serial No. 114,644.

The invention relates to car coupling apparatus designed particularly for coupling together the cars or tables employed in straight-away glass grinding and polishing operations. In such operations, the cars with the glass seated upon their upper faces, are moved in a continuous train beneath a series of grinding and polishing runners. It is necessary under these conditions that the cars be held tightly together, so that the upper surfaces constitute a continuous unbroken surface, and it is the primary object of the present invention to provide coupling apparatus of simple, reliable design, which will insure the maintenance of the car or table ends tightly in contact, regardless of vibration or strain tending to loosen the connections and permit the cars to spread apart. The coupling is also arranged to be operated automatically so as to disconnect the cars by a movement over a suitable cam when the cars arrive at a certain position of travel. Certain embodiments of the invention are illustrated in the accompanying drawings, wherein:

Figure 1 is a partial side elevation and partial section showing one form of the invention. Fig. 2 is a plan view. Fig. 2a is a section on the line a—a of Fig. 2. Fig. 3 is a vertical section showing another form of the invention. Fig. 4 is a partial horizontal section and partial plan view of the Fig. 3 construction. Fig. 5 is a section corresponding to that of Fig. 3, but with the parts in a different position. And Fig. 6 is a fragmentary side elevation view.

Referring to Figs. 1 and 2, the numerals 1 and 2 represent the bed plates of a pair of cars to which the coupling arrangement is applied. The cars are provided with racks 3 and 4 bolted securely to the car structures. These racks are engaged by pinions arranged at intervals along the line of travel of the cars for giving them their continuous forward movement beneath the series of grinding and polishing machines. These racks have nothing to do with the present invention, except that it so happens that certain parts of the coupling mechanism are supported upon the adjacent ends of these racks. Integral with the end of the rack 4 is a hook member 5 which constitutes one of the coupling members designed to cooperate with the downwardly facing hook member 6 carried by the other car. The

rack 3 has integral therewith a pair of upwardly extending bearing lugs 7, 7 in which is mounted the transverse pivot rod 8, such pivot rod being provided at its ends with the nuts 9, 9. Keyed to the ends of the pivot rod or shaft 8 are the toggle link members 10, 10 extending to the rear and carrying the pin 11. These toggle links 10, 10 are provided with downwardly extending lever arms 12, 12 having at their outer ends the weights 13, 13. These weights are provided on their lower sides with the rollers 14, 14 adapted to ride up on the cams 15 when the cars pass over such cams, such action serving to automatically uncouple the cars, as later described. In order to support the weights 13, 13 in raised position, a pair of latches 16 are provided pivoted upon brackets 17 and adapted to engage beneath the shoulders 18 formed upon the sides of the weights. The lower ends of the latches are normally pressed to the left by means of springs 19 encircling the stems 20 and engaging the washers 21. These latches are arranged so as to be moved to release position, as shown when the car ends 1 and 2 are brought into abutting relation, at which time the ends of the stems 20 engage the lugs 22 carried by the bed plate 2.

When the parts are in the position shown, the cars are tightly coupled together, as the weights 13 tend to swing the links 10, 10 in a counter clockwise direction around the pivot rod 8, and the movement of the pin along this arc, marked A in Fig. 1, tends to move the hook member to the left. Because of the toggle arrangement and the lever arms 12, the power as thus exerted, tending to pull the ends of the cars together is very considerable, and any vibration incident to the grinding and polishing operations and incident to the movement of the cars along the track tends to jar the weights downward and increase the pressure with which the car ends are brought into contact. The uncoupling is accomplished automatically by the cams 15 which are arranged in the line of travel of the cars. When the wheels 14 on the weights 13 engage these cams, the arms 12 are moved upward and the links 10, 10 swung in a clockwise direction around the pivot rod 8, so that the pin 11 moving upward along the arc A loosens the engagement of the hook member 6 with the opposing hook member 5. A

further upward movement of the links 10 causes the engagement of the rear ends 23 thereof with the lugs 24^a carried by the car body so that on a further movement of the parts upward, the hook member 6 is swung about the pin 11 as an axis until it is lifted clear of the hook member 5. At this time the roller 14 reaches the top of the cam 15 and the parts are maintained in the position specified until the rolls 14 pass down the inclines at the other ends of the cams 15, at which time the weights 13 are lowered until the shoulders 18 are engaged by the latches 16, the cars being separated at this time so that the stem 20 is to the right of the position shown, and the latches 16 are in position to engage the shoulders 18. This movement permits the links 10 to swing down until the hook member 6 again reaches a position such that it is in position for coupling when the end of the table is brought up against the end of another table. When two tables are thus brought together, the stems 20 of the latches are moved to the left, unhooking the latches and permitting the weights 13 to fall. This carries the hook member 6 to the left with great force so that the car ends are jerked tightly together. It will be seen from the foregoing that the coupler is automatic in its action and that the arrangement positively insures against the cars being separated. The use of the weights 13 is preferred as compared with springs, because their momentum tends to pull the parts more tightly together, but it will be understood that the invention is not limited to the use of weights for the purpose of continuously applying the tension for actuating the toggle arrangement.

Figs. 3, 4 and 5 illustrate a modification which in principle is the same throughout as the construction of Figs. 1 and 2. In this construction, the transverse shaft 24 is journaled in suitable bearings carried by the car body 25, and has keyed to its ends the levers or arms 26 provided with the weights 27. Mounted on the shaft 24 are the collars 28 having the elongated openings 29 therein and provided with the integral hook member 30, which corresponds with the hook member 6 of the Fig. 1 construction. A pair of collars 28^a (Fig. 4) secured to the shaft 24 by the set screws 28^b serve to hold the collars 28 and hook member 30 against movement longitudinally of the shaft 24. This hook member is adapted to cooperate with an opposing hook member 31 integral with the rack bar 32 carried by the car 33. The collars 28 and shaft 24 are provided with opposing recesses, as indicated in Fig. 3, and in these recesses are mounted the toggle links 34. The collar and hook member 30 are normally pressed yieldingly to the right by means of a pair of springs 35, 35 mounted upon the members 36, 36 engaging suitable recesses in the collars and in the vertical rib 37. When the parts are in the position illustrated in Fig. 3, the weights 27 tend to rotate the shaft 24 in a clockwise direction, thus forcing the toggle links 34 to the left and moving the hook member 30 to the left, so that the opposing faces of the cars are clamped tightly together. When the cars move to the left and the wheels 38 carried by the weights 27 ride upward along the cams 39, the shaft 24 is turned in a counter clockwise direction to the position of Fig. 5, thus permitting the springs 35 to move the collars and hook member 30 to the right and release the pressure between the hook members. After the shaft 24 has turned a certain amount, the shoulders 40 (Fig. 5) engage the lower faces of the link members 34 so that on a further movement, the collars 28 are rotated in a counter clockwise direction, thus lifting the hook member 30 so that it clears the hook member 31. The parts are maintained in this position until the rollers 38 ride downward on the other ends of the cams 39, at which time the shaft 24 again turns in a clockwise direction until the latch members, corresponding to the latch 16 in the Fig. 1 construction, come into play. These latch members are in the form of the arms 41, pivoted at 42^a and having the forwardly extending ends 43 adapted to be engaged by lugs 42 carried by the end of the car 33. The lower ends of the arms 41 are turned forward, as indicated at 44, and pressed yieldingly upward by the springs 45 mounted upon the bolts 46. The arms 41 are provided with catch shoulders 47 adapted to engage opposing shoulders 48 carried by the hubs 49 of the lever arms 26, so that when the hook member 30 in its downward movement arrives at the position shown in Fig. 3, the catch shoulders 47 engage the shoulders 48 and in this manner the hook member 30 is held in coupling position. The arms 41 are moved to the rear to permit the weights 27 to fall to the position illustrated in Fig. 3, when two cars are brought into abutting relation, at which time, the lugs 42 move the arms 41 to the left so that the weights drop and pull the car ends tightly together, as in the other type of construction.

What I claim is:

1. In combination in coupling apparatus for a car, a coupling hook member mounted for longitudinal and vertical swinging movement on said car, and adapted to be hooked over a projection on an adjacent car, pivot means fixed in the end of the car, toggle link means between the pivot means and the hook member, arranged to move the hook member so as to draw it inward towards the projection on the adjacent car to

- thereby draw the cars together as the link means swings in one direction, means for yieldingly forcing the link means in such direction, a latch for holding the link means 60 in its reverse position, and means for releasing the latch.
2. In combination in a coupling apparatus for a car, a coupling hook member mounted for longitudinal and vertical swinging movement on said car, and adapted to be hooked over a projection on an adjacent car, pivot means fixed in the end of the car, toggle link means between the pivot means and the hook member, arranged to move the 65 hook member so as to draw it inward towards the projection on the adjacent car to thereby draw the cars together as the link means swings in one direction, means for yieldingly forcing the link means in such direction, a latch for holding the link means 70 in its reverse position, and means for releasing the latch, positioned so as to be operated by the adjacent car as it comes into abutting relation therewith.
3. In combination in coupling apparatus for a car, a coupling hook member mounted for longitudinal and vertical swinging movement on said car, and adapted to be hooked over a projection on an adjacent car, pivot means fixed in the end of the car, toggle link means between the pivot means and the hook member, arranged to move the 75 hook member so as to draw it inward towards the projection on the adjacent car to thereby draw the cars together as the link means swings in one direction, a weighted lever for yieldingly forcing the link means in such direction, arranged so as to be lifted by cam means located along the line of travel of the car and adapted to move the link means to reverse position, a latch for holding the lever in its raised position with the link means in reversed position, and means operated by the adjacent car as it comes into abutting relation therewith for releasing the latch. 80
4. In combination in coupling apparatus for a car, a coupling hook member mounted for longitudinal and vertical swinging movement on said car, and adapted to be hooked over a projection on an adjacent car, pivot means fixed in the end of the car, toggle link means between the pivot means and the hook member, arranged to move the 85 hook member so as to draw it inward towards the projection on the adjacent car to thereby draw the cars together as the link means swings in one direction, a weighted lever for yieldingly forcing the link means in such direction arranged so as to be lifted by cam means located along the line of travel of the car and adapted to move the link means to reverse position, a latch for holding the lever in its raised position with the link means in reversed position, and means operated by the adjacent car as it comes into abutting relation therewith for releasing the latch. 90
5. In combination in coupling apparatus for a car, a coupling hook member mounted for longitudinal and vertical swinging movement on said car, and adapted to be hooked over a projection on an adjacent car, pivot means fixed in the end of the car, toggle link means between the pivot means and the hook member, arranged to move the 95 hook member so as to draw it inward towards the projection on the adjacent car to thereby draw the cars together as the link means swings in one direction, a weighted lever for yieldingly forcing the link means in such direction arranged so as to be lifted by cam means located along the line of travel of the car and adapted to move the link means to reverse position, a latch for holding the lever in its raised position with the link means in reversed position, and means operated by the adjacent car as it comes into abutting relation therewith for releasing the latch. 100
4. In combination in coupling apparatus for a car, a coupling hook member mounted for longitudinal and vertical swinging movement on said car, and adapted to be hooked over a projection on an adjacent car, pivot means fixed in the end of the car, toggle link means between the pivot means and the hook member, arranged to move the 105 hook member so as to draw it inward towards the projection on the adjacent car to thereby draw the cars together as the link means swings in one direction, a weighted lever for yieldingly forcing the link means in such direction arranged so as to be lifted by cam means located along the line of travel of the car and adapted to move the link means to reverse position, a latch for holding the lever in its raised position with the link means in reversed position, and means operated by the adjacent car as it comes into abutting relation therewith for releasing the latch, the parts being so arranged that the upward movement of the weighted lever first causes the hook member to move forward and then causes it to move upward to 110 disengage it from the abutment on the adjacent car so that the cars may be drawn apart.
- In testimony whereof, I have hereunto subscribed my name this 6th day of May, 115 1926.

HALBERT K. HITCHCOCK.
